UNITED STATES PATENT OFFICE.

RICHARD LAHEY, OF NEW YORK, N. Y., AND EDWARD GRAFFIUS, OF SAULT STE. MARIE, MICHIGAN.

MACHINE FOR USE IN CONNECTION WITH DERRICKS.

SPECIFICATION forming part of Letters Patent No. 769,264, dated September 6, 1904.

Application filed March 24, 1904. Serial No. 199,836. (No model.)

To all whom it may concern:

Be it known that we, RICHARD LAHEY, a resident of New York, county and State of New York, and EDWARD GRAFFIUS, a resident 5 of Sault Ste. Marie, county of Chippewa, and State of Michigan, citizens of the United States, (our temporary address being Ford, in the county of Clark and State of Kentucky,) have invented certain new and useful Improvements 10 in Machines for Use in Connection with Derricks, of which the following is a specification.

One of the main features of our invention consists of novel and useful mechanism to advantageously supersede certain mechanism now in use on double-drum hoisting-machines.

Another of the main features appertains to the means employed and their arrangement relatively to the "bull-wheel" of a derrick.

20 The several features of our invention and the various advantages resulting from their employment conjointly or otherwise will be apparent from the following description and claims.

25 We will now proceed to describe our invention in detail.

In the accompanying drawings, in which similar characters of reference indicate corresponding parts, Figure 1, Sheet 1, is a view 30 in perspective of a hoisting-engine, apparatus, derrick, and its apparatus, illustrating our invention. The following-named figures are on a larger scale. Fig. 2 is a perspective view, on an enlarged scale, of the hoisting-engine and its apparatus shown in Fig. 1. Fig. 3 is a

perspective view showing the basal part of the derrick, the lower portion of the boom, and the bull-wheel. Fig. 4, Sheet 2, is a side elevation of the wheels and the adjacent portion 40 of the chain for operating the bull-wheel. This figure also illustrates a part of the mechanism employed for operating the clutches which set either of these wheels in motion or put either or both at rest. Fig. 5 is a top

45 view of the mechanism presented in Fig. 4 and of one of the foundation-pieces; but the parts N and P and the adjacent portions of chain Q are omitted from this figure. Fig. 6 is a horizontal section of either driving sprocket-

wheel, its clutch-wheel, a part of its shaft, and 50 the mechanism on the shaft for operating the clutch. Fig. 7 is an edge view of either of the levers directly connected to a nut on a shaft and which nut is adapted to advance and retract the clutch. Fig. 8 is a side elevation of 55 the lever shown in Fig. 7. Fig. 9 is a side elevation of the lever operating the links respectively connected to the levers illustrated in Figs. 7 and 8. Fig. 10 is a view of the preferred form of teeth present on the periphery 60 of either of the sprocket-wheels. This view is one looking directly at the periphery of the wheel and an axial plane coincident with the wheel. Fig. 11 is a perspective view of a journal box or bearing viewed at a point in 65 the vicinity of the clutch located on the shaft which turns in this box. Fig. 12 is a perspective view of that end of the screw-sleeve which is secured to this box.

A indicates a suitable basal foundation. 70 On this are located the journal-boxes B. In one of these the shaft C rotates and in the other the shaft D rotates. These shafts are duly rotatable by electrical, steam, or other power. In the present illustrative instance 75 I have shown a steam derrick-engine in connection. Of this W is the boiler, X is the steam-cylinder, X² the pitman of the engine, X³ the crank, X⁴ the driving-shaft. This shaft is adapted to rotate the shafts C and D 80 and either of the hoisting-drums R when connected thereto. In the present illustrative instance this connection is made by a friction-clutch.

With the shaft C is combined a clutch E, 85 and with the shaft D is combined a clutch F. Inasmuch as the construction of both clutches and the means for immediately operating them is substantially the same, the description of one clutch will answer for both. The shaft 90 C or D, as the case may be, is prevented from slipping forward through the box by the collar S, fastened to the shaft by a set-screw S². This collar preferably abuts the box B. At the other end of the box is a sleeve T, carrying 95 a male screw-thread T² and provided with a radial flange T³. The upper half of this radial flange is, as shown, preferably smaller than

the lower half. The radial flange preferably abuts the box B at that end of it which is opposite to the collar S. This flange T³ is secured in place, and the preferred means are as follows:

- 5 A screw is located in the flange and screwed into the boxing B at B². On the flange T³ are cast square lugs T⁴, which fit in a groove between the upper and lower parts of boxing B and prevent the flanges T³ from turning.
 10 This groove is preferably recessed out of the lower half of the box or bearing B. Of course the shaft which the sleeve T embraces turns freely within it.

V indicates a nut having a female screw-thread V² and a radial flange V³. This nut V is screwed onto the screw-thread T² of the sleeve T. The flange V³ is at a distance from the flange T³ and abuts, preferably, directly against the side of the adjacent member G of 15 the clutch E. This member G is mounted on the shaft and is compelled to turn with it; but it can slide along the shaft toward and from the fixed sleeve T. One or more feathers or keys G² between the shaft and the 20 clutch member G and projecting into both allow the clutch member G to thus move along the shaft in the direction of the length of the latter. Beyond this clutch member G is the 25 clutch member H, and the adjacent faces of these members are shaped so as to frictionize 30 each other when brought into contact. When the clutch members are apart, there is a space between them, somewhat as shown in Fig. 6. The preferred construction of the friction-face 35 of clutch G is as follows: There is a wedge-shaped ring G⁴, and when made separately from the discal portion G³ of the clutch G it is secured in place by bolts G⁵ and nuts G⁶. The central portion G⁷ of this clutch member 40 G is preferably convexly formed, as shown. The opposite clutch member H has an annular recess H² to receive the ring G⁴ and has also a concave central portion H³ to receive the part G⁷. It has also in the vicinity of the 45 shaft C a part H⁴ sufficiently large to afford the clutch H a sufficient bearing on the shaft C. This clutch H turns loosely on the shaft except when forced by the other members of the clutch to rotate with it. A convenient 50 means for preventing the clutch H from slipping off the shaft is the disk I, secured to the shaft by bolts I². When the nut V is screwed up against the sleeve T and the clutch member G is against the flange V³ of the nut V, 55 there will be sufficient space between the clutch members G and H to allow the latter member to be out of contact with the member G. When the nut V is screwed forward on the sleeve T toward clutch member H, it will 60 force the clutch member G into contact with the clutch member H, and therefore, then, the clutch member H will rotate with the clutch member G. The means for operating these 65 clutches are as follows: On a framework J, connected to and supported by the boxes B B,

I locate a journal-bearing J². In this bearing is a pivot or journal J³, connected to an upright lever J⁴. Connecting rods or strips J⁵ J⁶ are present. One of these extends from the lever J⁴ to lever K² of the sleeve V, and the other of these extends from the lever J⁴ to the lever K² of the other sleeve V. These levers K² are each provided with rings K, and the latter are preferably split rings and provided with a bolt K⁴, passing through the extensions or lugs K³ of these rings and secured by a nut K⁵. Each ring K embraces its adjacent sleeve V, and with the bolt K⁴ K⁵ the ring is clamped on its sleeve in the proper position and tightly, so that the ring and sleeve turn together. Thus by moving the lever J⁴ the levers K² will be moved and the rings and their sleeves turned. The throw of the levers K² will be greater or less according as the pivot J⁶, whereby they are connected to the lever J⁴, is located higher up or lower down on this lever. Such change of location is readily made by putting this pivot into the desired one of a number of holes (lettered J⁷) and located in the lever J⁴, as shown. We 70 prefer to connect the lever J⁴ to the shaft J³ by an adjustable connection. This is preferably as shown and consists of the sleeve J⁸, split at its lower end and provided with the extension-lips J⁹ J¹⁰, united by a screw or bolt 75 J¹¹. The lever J⁴ being set in the proper position relative to the shaft J³ the lips J⁹ J¹⁰ are approximated, and the lever J⁴ is thus set on the shaft. The shaft J³ may be positively operated by any suitable means. One means 80 is a lever J¹², fixed on the shaft J³ at J¹³.

It is to be noted that when both of the levers K² are above the horizontal plane of the shaft, as shown, one of the nuts screws forward in a direction the opposite of the other. If one of the levers was above and one below 85 said plane, the screws of the nuts might both be in the same direction.

We will now proceed to describe another 90 feature of our invention.

On the clutch E—to wit, on the outer member (in the present illustrative instance the member H)—we fix a gear-wheel L of the sprocket order, adapted to engage with the links of a suitable chain Q, and on the clutch F (member H) we fix a similar gear-wheel M. Each of these gear-wheels L and M is preferably attached to its respective member H by bolts. At a suitable place I locate an idle wheel N. This latter is pivotally connected to a journal-bearing, adjustable so that the wheel N can be moved nearer to or farther from the wheels L and M. The adjustment can be made by screw; but it can be made, as shown, by perforations P² in the pieces P, for there are two of these—one on each side of the idle wheel N—and these are adapted to receive the pivot N². The pivot N² if placed in the opposing holes P² near the wheels L and M, locate the idle wheel N nearer to them, 100 105 110 115 120 125 130

and vice versa. The opposite end of each of the pieces P is duly secured to a foundation. The sprocket-chain Q passes partly around the gear-wheel L, and then partly around the 5 idler (idle wheel) N, and then partly around the gear (sprocket) wheel M, and then onto the bull-wheel 1. The chain Q may be in two parts. It is duly fixed to the bull-wheel at a proper point or points on the periphery of the latter. Movement of the chain back or forth therefore operates to rotate the wheel. The connection between the chain and bull-wheel, so as to rotate the latter, could be accomplished by providing the peripheral sur- 10 face of the bull-wheel with projections after the manner of a sprocket-wheel, or the connection might be made by having the chain embrace the bull-wheel and be fastened permanently to the bull-wheel at that side of the 15 wheel opposite to where the parts of the chain Q run out toward the winding-drums; but the preferred construction is as shown in Fig. 3. From the bull-wheel the chain Q passes back 20 and around the wheels L, M, and N, as heretofore described, and then back again to the bull-wheel. The bull-wheel in the present 25 illustrative instance is, as usual, attached to the mast 3, resting in a suitable step or pivot-hole. The mast or its connection carries a 30 boom 4. The latter may be located at the foot of the mast, as shown, or elsewhere. The mast will be suitably supported by guys or braces. In the drawings braces are shown. It is noted that the function of the bull-wheel 35 is to rotate the mast and the boom. In connection with the mast and the boom and the engine there will be present suitable means for hoisting the load to be moved and for lowering it. These are well known. As they 40 constitute no part of the present invention, further mention of them is omitted.

The manner in which our invention operates is as follows: When the bull-wheel is to be turned a given direction, the lever J¹² is 45 moved toward the boiler. This screws the nut V on the sleeve T away from the boxing B and tightens its clutch E and at the same time screws up the nut on the shaft D toward the boxing B and loosens the clutch F. The engine moving rotates the sprocket-wheel L positively and moves the chain Q in the desired direction, thus rotating the bull-wheel and turning the mast and moving the boom as desired. To move the boom, mast, and 50 bull-wheel in an opposite direction, the lever J¹² is moved into a position the reverse of that which it heretofore occupied. Such a movement causes the nut V on sleeve T of shaft D to force the adjacent clutch member G against 55 clutch member H and the nut V of shaft C to move back and liberate the adjacent clutch member G from its clutch member H. Thereupon the sprocket-wheel M will rotate in a direction the same as that in which the 60 wheel L revolved. The chain Q will thus be

65 moved in an opposite direction and the bull, mast, and boom will be moved in the like opposite direction. To suspend the movement of both of the wheels L and M, we move the lever J¹² to a mid-position. (Seen in Figs. 2 70 and 4.) Then the nuts V V are in such a position as to leave both members G G out of engagement with their opposing clutch members H H. It will be understood that while the engine continues to revolve in one direction the shafts C and D, driven thereby through gearing, are so geared as that the shaft C 75 revolved in a direction the same as that of the shaft D.

Some of the advantages of our invention are 80 the following: The construction of the means for operating the clutches is not only novel, but it is very simple, economical, and advantageous. The organization of the wheels L and M and the chain and the bull-wheel I and 85 the auxiliary wheel N is very advantageous. The action thereof is very positive and accurate. When the hoisting apparatus is first set up and thereafter, all surplus slack present in the chain Q is taken up by this auxiliary wheel N. The necessary tension of the 90 chain Q relative to the apparatus can be readily adjusted by setting the wheel N nearer to or farther from the wheels L and M, as will be well understood.

What we claim as new and of our invention, 95 and desire to secure by Letters Patent, is—

1. In a hoisting apparatus, a driving-shaft, a clutch member as regards rotation fixed thereto, but slidable on the shaft, a clutch member when out of use turning loosely thereon, a stationary sleeve on this shaft, and provided with a screw-thread, a nut whose screw engages that of the sleeve, the nut being in connection with the first-named clutch member, and means for rotating the nut, for causing 100 the clutch to become operative, or inoperative, at will, substantially as and for the purposes specified.

2. In a hoisting apparatus, the two driving-shafts, rotatable in the same direction, each of which is provided with the following-described mechanism, viz: a clutch member as regards rotation fixed thereto, but slidable on the shaft, a clutch member when out of use 105 turning loosely thereon, a stationary sleeve on this shaft, and provided with a screw-thread, a nut whose screw engages that of the sleeve, the nut being in connection with the first-named clutch member, and means for simultaneously 115 rotating these nuts in opposite directions, for rendering either clutch operative, or both inoperative, substantially as and for the purposes specified.

3. In a hoisting apparatus, a driving-shaft, 120 a clutch member, when out of use, turning loosely thereon, a clutch member turning with the shaft, the journal bearing or box of the shaft, a stationary sleeve on this shaft, provided with a screw-thread, and fixed to said 125 130

journal-bearing, a nut whose screw engages that of the sleeve, the nut being in connection with the slidable clutch member, and means for rotating the nut for causing the clutch to become operative or inoperative, at will, substantially as and for the purposes specified.

4. In a hoisting apparatus, a driving-shaft, a clutch member, when out of use, turning loosely thereon, a clutch member turning with the shaft, and connected to the shaft by a key longitudinal with the shaft, the journal bearing or box of the shaft, a stationary sleeve on this shaft, provided with a screw-thread, and fixed to said journal-bearing, a nut whose screw engages that of the sleeve, the nut being in connection with the slidable clutch member, and means for rotating the nut for causing the clutch to become operative or inoperative, at will, substantially as and for the purposes specified.

5. In a hoisting apparatus, the two driving shafts, rotatable in the same direction, each of which is provided with the following-described mechanism, to wit: a clutch member, a key between the shaft and this clutch member, a clutch member, when out of use, turning loosely on said shaft, a stationary sleeve having a screw-thread, a nut whose screw engages that of the sleeve, and is in conjunction with the first-named screw member, each nut in connection with its adjacent slidable clutch member, the screw and nut of the one shaft operating in an opposite direction from the screw and nut of the other shaft, each nut provided with its lever, and a central lever mounted on a shaft, means for operating the latter shaft, connecting-rods respectively connected at one end to the lever of the nut and at the other end to the central lever, substantially as and for the purposes specified.

6. In a hoisting apparatus, the two driving shafts, rotatable in the same direction, each of which is provided with the following-described mechanism, to wit: a clutch member, a key between the shaft and this clutch member, a clutch member, when out of use, turning loosely on said shaft, a stationary sleeve having a screw-thread, a nut whose screw engages that of the sleeve, and is in conjunction with the first-named screw member, the screw and nut of the one shaft operating in an opposite direction from the screw and nut of the other shaft, each nut provided with its lever, means for rendering said lever capable of adjustment, relative to the nut, a central lever mounted on a shaft, means for operating the latter shaft, connecting-rods respectively connected at one end to the lever of the nut and means for connecting these rods to the central lever whereby the throw of the nut-levers can be increased or diminished, substantially as and for the purposes specified.

7. In a hoisting-machine, a bull-wheel, a chain engaging said wheel, two driving

sprocket or chain wheels, and an auxiliary 65 wheel, the driving-wheels adapted to rotate in opposite directions, when either one is clutched, the chain of the bull-wheel passing upon one sprocket-wheel, then upon the auxiliary wheel and then upon the other sprocket- 70 wheel, and mechanism adapted to throw either one of these wheels into positive operation, while the other is negative, or to throw both out of operation, substantially as and for the purposes specified.

8. In a hoisting-machine, a motor, two driving sprocket or chain wheels, and an auxiliary wheel, the shafts of these driving-wheels rotatable in the same direction, means for simultaneously putting either one into driving 80 action and the other out of such action, a bull-wheel for rotating the derrick-mast, and boom, a chain connected to said bull-wheel, and engaging these sprocket-wheels and the auxiliary wheel, and means whereby the auxiliary 85 wheel may be moved nearer to or farther from the driving-wheels, substantially as and for the purposes specified.

9. In a hoisting-machine, a motor, two driving sprocket or chain wheels, and an auxiliary 90 wheel, the shafts of these driving-wheels rotatable in the same direction, means for simultaneously putting either one into driving action and the other out of such action, a bull-wheel for rotating the derrick-mast, and boom, 95 a chain connected to said bull-wheel, and engaging these sprocket-wheels and the auxiliary wheel, and the journal-bearing rods P, provided with openings P², for the reception of the journal of the auxiliary wheel, substantially as and for the purposes specified.

10. In a hoisting apparatus, a pair of driving-shafts turning in the same direction, clutches mounted thereon, stationary sleeves with screw, also thereon nuts whose screws 105 respectively engage the screws of the sleeves, the inclines of the screw of one nut and sleeve reversed as to those of the other, means for operating these nuts, whereby either clutch may be put in action while the other is out of action, a sprocket-wheel on one member of each clutch, an auxiliary wheel, a bull-wheel, a chain, engaging the bull-wheel, and the other wheels, substantially as and for the purposes specified.

11. In a hoisting apparatus, a pair of driving-shafts turning in the same direction, clutches mounted thereon, stationary sleeves with screw, also thereon nuts whose screws 110 respectively engage the screws of the sleeves, the inclines of the screw of one nut and sleeve reversed as to those of the other, adjustable means for operating these nuts, whereby either clutch may be put in action while the other is out of action, a sprocket-wheel on one member of each clutch, an auxiliary wheel, a bull-wheel, 115 a chain, engaging the bull-wheel, and the other wheels, and means for enabling the

auxiliary wheel to be set nearer to or farther from the other sprocket-wheel, substantially as and for the purposes specified.

12. In a hoisting-machine, a driving-shaft, 5 a clutch member as regards rotation fixed thereto, but slidable on the shaft, a clutch member when out of use turning loosely thereon, a stationary sleeve located on this shaft and provided with a screw-thread, this 10 sleeve provided with a flange, and with the lugs therefrom, one of the boxes recessed to receive these lugs, means for holding the lugs in the recess, a nut whose screw engages that of the sleeve, the first-named clutch member

being located for a forward movement of the 15 nut to advance it, and means for rotating the nut for causing the clutch to become operative or inoperative at will, substantially as and for the purposes specified.

In testimony whereof we have set our hands 20 to this specification in the presence of two subscribing witnesses.

RICHARD LAHEY.
EDWARD GRAFFIUS.
